EVAPORATOR STRUCTURE

Joseph N. Roth, Belding, Mich., assignor to Gibson Electric Refrigerator Corporation, a corporation of Michigan

Application May 17, 1941, Serial No. 394,031

7 Claims. (Cl. 62—126)

This invention relates to an evaporator structure, and more especially to an evaporator structure particularly designed for domestic refrigerators, and to an improved method of manufacturing such a structure.

One feature of this invention is that it provides an improved freezing compartment with heat-removing coils both above and below; another feature of this evaporator structure is that it comprises loops of tubing and a sheet metal box; yet another feature is an improved method of forming, assembling and joining the parts of the evaporator structure; a further feature is the provision of means for fastening a tube in intimate heat exchange relation with a sheet metal plate by spot welding, as a rapid factory operation, without danger of burning through thin steel tubing; still another feature is the use of tubing of different internal diameter in different portions of the evaporator structure, and a particular arrangement of the tubing, to provide smoother freezing action throughout the whole of the evaporator structure; and yet another feature is the provision of an improved junction between a capillary tube and an evaporator tube to prevent frosting back through the cabinet wall.

Other features and advantages of this invention will be apparent from the following specification and the drawings, in which:

Figure 1 is a vertical cross-sectional view of the food compartment of a domestic absorption refrigerator; Figure 2 is a top plan view of the evaporator and its connections, the back insulated wall of the food compartment being shown in dotted lines; Figure 3 is a view along the line 3—3 of Figure 2; Figure 4 is a back view of the evaporator; Figure 5 is a bottom view of the structure shown in Figure 2; Figure 6 is a fragmentary detail view along the line 6—6 of Figure 4; Figure 7 is a detail sectional view of the junction between the capillary tube and the inlet side of the evaporator tube; Figure 8 is a top view of another form of evaporator; Figure 9 is a bottom view of the evaporator shown in Figure 8; and Figure 10 is a side view, partly in section, of this last form of evaporator.

Shelf or flat plate types of evaporators have met with increasing favor in domestic refrigerators, yet such evaporators present certain problems, particularly with regard to uniform cooling and with regard to their manufacture and assembly. I have provided an improved evaporator with upper and lower cooling coils, the lower coils providing uniform cooling over the entire area of the shelf of the evaporator, and the

arrangement of the two sets of coils being such that a considerable amount of the refrigerant is forced up into the upper coils in liquid state to complete its vaporization there, so that even at low rates of refrigeration or operation of the refrigerator considerable cooling takes place from above. I have also found that my particular arrangement of evaporator can be best manufactured by welding and forming the tubing to the desired shape over forms or jigs, separately forming a sheet metal box structure, slipping the tubing over the box structure, and then attaching the two in intimate heat exchange relation by clips or fastening members straddling the tube and spot welded to the sheet metal on each side of the tube at a plurality of spaced points. Moreover, I provide a connective arrangement between the evaporator tubing and capillary tubing such that frosting back through the insulated food compartment wall is prevented without the necessity of an accumulator.

Referring now to Figures 1 to 7 of the drawings, a domestic refrigerator is shown having a food compartment 10 with insulated walls 11. While my evaporator has advantages in any type of domestic refrigerator, it was designed for a continuous absorption refrigerator, wherein its advantages are realized to the fullest. The evaporator is shown in the top of the food compartment 10, and comprises a sheet metal box 12 and upper and lower loops of tubing.

Referring now more particularly to Figures 2, 3, 4 and 5, liquid refrigerant delivered to the capillary housing 13 passes through the back insulated wall 11 of the food compartment through the tube 14, the details of this connection being described more fully hereafter. In Figure 5 it will be seen that the flow path of the refrigerant passes along the tube 15 and through the tubes 16, 17, and 18 to pass substantially entirely around the periphery of the bottom plate 19 of the evaporator box or shell, this plate 19 forming a shelf having substantially the same cross-sectional area as that of the food compartment, and adapted to have ice cube trays and the like placed on its upper surface. The tubing is then looped back and forth in contact with the remaining area of this plate bounded by the above-mentioned tubing, the legs of these loops being here indicated as 20, 21, 22, 23 and 24. The flow path then continues through the tube 25 to the back of the evaporator and up through the tube 26 (see Figure 4) to the upper section of the evaporator. Referring more particularly to Figure 2, a top view of the evaporator, it will be seen that when

the tubing reaches the upper level it expands in diameter at 27, then extends forwardly to the front edge of the top of the evaporator shell and loops back and forth again, the legs of these latter loops being indicated as 28, 29, 30, 31, 32 and 33. The refrigerant then passes down through the tube 35 (also see Figure 4) and out through the back wall of the food compartment to join, preferably with a flanged coupling, to the pipe 36 leading to part of the refrigerant circulating apparatus, this pipe leading to the absorber in a continuous absorption refrigerator.

While a number of different reference numerals have been used on various sections of tubing for clarity of description, it will be understood that there is a single continuous tube or refrigerant flow path from the inlet section 14 to the outlet section. While for purposes of manufacturing convenience this single continuous flow path may be formed by welding together various sections of tubing, in finished form it is in effect a single tube looping back and forth in a lower horizontal plane and then passing up to a higher plane parallel to but spaced from the first-mentioned plane. By first passing the tubing substantially entirely around the periphery of the freezing shelf or bottom plate of the evaporator shell, and then looping it back and forth over the remaining area, cooling is substantially uniform over the entire area of this shelf. This is important, since heretofore considerable difficulty has been encountered in that an ice tray placed on one side of a freezing shelf might freeze rapidly while an ice tray placed on the other end of the same shelf might never freeze.

Moreover, although it has been known to be desirable to provide some cooling effect above the evaporator shell in these types of evaporators, heretofore the upper tube sections have only been effective when the refrigerator was operating at a high rate and delivering a considerable amount of liquid refrigerant to the evaporator. I have overcome this difficulty and caused a certain amount of the liquid refrigerant to pass on up into the upper section of the evaporator even at low refrigeration rates by making the upper and lower portions of tubing of different internal diameter, the tubing of the upper portion preferably having an internal diameter fifty per cent or more greater than that of the tubing in the lower portion. In a particular embodiment of my invention I find that my desired results are secured by making the lower tubing section of tubing of three-eighths inch outer diameter and one-quarter inch internal diameter, and the upper section of tubing of nine-sixteenths inch outer diameter and seven-sixteenths inch internal diameter.

In manufacturing an evaporator of the kind here disclosed I find it preferably to form and weld the various tubing sections over forms and jigs, forming the tubing to finished shape. I then separately form the sheet metal box or shell by such bending and welding operations as may be necessary. As may be best seen from Figure 3, the sheet metal shell can then be slipped in between the upper and lower tubing sections, so that the two are brought into finished relation. The tubing is then permanently attached to the shell and held in intimate heat exchange relation with it by the use of clips or fastening members which straddle the tube and are spot welded to the sheet metal on each side.

It will be seen that there are a number of these fastening members overlying the tubing at

regularly spaced intervals, as about every five or six inches. Since they are all duplicates only one, here identified as 37, will be described.

Referring more particularly to Figure 6, it will be seen that the fastening member 37 is of strap metal, as thin steel strip, having an arcuate or U-shaped center portion and flat outwardly extending end portions identified as 38 and 39. The U-shaped center portion is made with such a curvature as to just conform to the outer surface of the tube 33, and of a depth slightly less than the diameter of the tube. That is, in their original shape the end portions of the fastening member extend out parallel to the plate 40, but not quite in contact therewith because of this slight difference between the depth of the center portion and the outer diameter of the tube. The mechanical action of forcing them down into engagement with the plate and spot welding them thereto, therefore, places them under strain so that the tube 33 is pulled down tightly against the plate 40 and held in intimate heat exchange relationship with it.

For a number of reasons it is desirable to use rather thin steel tubing and light sheet metal plates in an evaporator of the type here disclosed. Heretofore tubing has generally had to be brazed or soldered in engagement with the sheet metal, not nearly as rapid and satisfactory as spot welding, because spot welding such light steel tubing directly to the plate frequently burned through the tubing and resulted in openings which caused rejection of the evaporator on inspection, or weak spots which caused leakage after only a short period of use of the evaporator. The use of fastening members or clips secures all the desirable features of spot welding, such as rapidity and permanence, without any danger of damage to the tubing. Soldering is particularly undesirable, for example, where it is desired to subject the evaporator in finished form to considerable heat, as where enamel is baked on or the structure is hot dip galvanized.

Referring now more particularly to Figure 7, it will be seen that the tube 14 passing through the insulated back wall 11 of the food compartment is considerably reduced in internal diameter with respect to the evaporator tube 15 with which it connects. Control of the admission of refrigerant to the evaporator is achieved by a capillary tube terminating in a straight portion 41 extending through the back wall and received in a fairly close fit by the tube 14. The other details of the capillary arrangement are not illustrated here, forming the subject matter of my copending application Serial No. 361,629, filed November 17, 1940. The capillary is carried by a plate 42 providing a flange adapted to be bolted or otherwise removably sealed to a flange 43 welded to the outer end of the tube 14. This construction facilitates assembly and disassembly of the parts since the evaporator may be first located in the cabinet, the capillary 41 slipped into the pipe 14 until the plate 42 contacts the flange 43, and then the parts may be fastened together by bolts. This enables the final connection to be made from the outside of the food compartment, although the delivery end of the capillary tube actually lies within the food compartment. For purposes of design the capillary tube lies at a slightly lower level than the lower horizontal portion of evaporator tubing, so that the refrigerant has to pass uphill from the end of the evaporator to the lower section. Heretofore accumulators have been used to prevent frosting back through the

insulated wall under such circumstances, but I have found that this can be eliminated where the connector tube 14 is of small diameter, as illustrated. If the capillary tube 41 is a fairly close fit within this tube 14 liquid refrigerant cannot run back through the tube 14 to the outside of the insulated wall to cause frosting of the flange 43 and its associated parts.

Turning now to Figures 8, 9 and 10, another form of flat shelf evaporator is shown which embodies the feature of uniform cooling of the shelf surface. As may be best seen in Figure 8, the refrigerant enters through the tube 45 and then passes substantially entirely around the periphery of the plate 46 through the portions 47, 48 and 49. Thereafter, as in the first described form of my invention, it loops back and forth over the remaining area of the evaporator, the legs of the loops being here indicated as 50, 51, 52 and 53. Thereafter the tubing drops down an inch or so and loops back and forth in the other direction, out of contact with the plate and slightly below the above-described loops, in loops having legs identified as 54, 55, 56, 57, 58, 59 and 60, the refrigerant then passing out through the outlet pipe 61. This additional tubing below and out of contact with the plate furnishes further vaporization space for the refrigerant when the refrigerator is operating at a high rate, so that frosting never takes place outside of the food compartment.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In a continuous absorption refrigerator having a food compartment, an evaporator including: a horizontal metal plate of an area substantially equal to the cross-sectional area of the food compartment; and a tube adapted to have refrigerant flow therethrough, the tube having a portion in heat exchange relation with the plate and first passing substantially entirely around the plate near the periphery thereof, then looping back and forth in serpentine bends in contact with the remaining area of the plate, then extending to and looping back and forth in another plane parallel to and above said plate, the portion of the tube in the upper plane having a length substantially equal to that in the lower plane and having an internal diameter at least 50% larger than that of the portion in the lower plane.

2. In a continuous absorption refrigerator having a food compartment, an evaporator in-

cluding: a horizontal metal plate of an area substantially equal to the cross-sectional area of the food compartment; and a tube adapted to have refrigerant flow therethrough, the tube having a portion in heat exchange relation with the plate and first passing substantially entirely around the plate near the periphery thereof, then looping in contact with the remaining area of the plate, then extending to and looping in another plane parallel to said plate, the internal diameter of the latter portion of the tube being larger than that of the portion in heat exchange relation with the plate.

3. Apparatus of the character claimed in claim 2, wherein the two portions are of substantially equal length.

4. Apparatus of the character claimed in claim 2, wherein the plane in which the latter portion of the tube lies is above that of the plate.

5. Apparatus of the character claimed in claim 2, wherein the portion of the tube looping back and forth makes serpentine bends.

6. In a continuous absorption refrigerator having a food compartment, an evaporator including: a horizontal metal plate of an area substantially equal to the cross-sectional area of the food compartment; and a tube adapted to have refrigerant flow therethrough, the tube having a first portion in heat exchange relation with the plate and a second portion in another horizontal plane parallel to the plate, the internal diameter of the first portion of the tube being small enough and its arrangement such that the flow of liquid refrigerant through said first portion is accelerated and there is a substantially uniform distribution of cooling effect throughout the entire area of said plate at all refrigeration rates, the internal diameter of the second portion being large enough to permit liquid refrigerant to vaporize therein without appreciable acceleration of liquid flow.

7. In a continuous absorption refrigerator having a food compartment, an evaporator including: a horizontal metal plate of an area substantially equal to the cross-sectional area of the food compartment; and a tube adapted to have refrigerant flow therethrough, the tube having a first portion with at least a part thereof in heat exchange relation with the plate and a second portion in another horizontal plane parallel to the plate, the construction and arrangement of the tube being such that the flow of liquid refrigerant through said first portion is accelerated and there is a substantially uniform distribution of cooling effect throughout the entire area of said plate at all refrigeration rates while the flow of liquid refrigerant through the second portion is substantially unaccelerated.

JOSEPH N. ROTH.
